UNITED STATES PATENT OFFICE.

BENJAMIN WEXLER, OF NEW YORK, N. Y.

VERTICALLY-SLIDING DOOR FOR ELEVATOR-SHAFTS.

1,197,317.

Specification of Letters Patent.

Patented Sept. 5, 1916.

Application filed September 2, 1915. Serial No. 48,593.

To all whom it may concern:

Be it known that I, BENJAMIN WEXLER, a citizen of the United States, and a resident of New York city, borough of Brooklyn, in the county of Kings and State of New York, have invented certain new and useful Improvements in Vertically-Sliding Doors for Elevator-Shafts, of which the following is a specification.

10 This invention relates to improvements in vertically sliding doors for elevator shafts. Elevator doors made in accordance with my invention belong to a type of door embodying therein a plurality of counter-weighted sections, all of which have simultaneous movement in the same direction, but at varying speeds, to facilitate the rapid opening and closing of the doors and to permit the use of large door openings and doors 20 relatively to the space between the lintel of a door opening on one floor and the sill of the door opening on the floor above. Heretofore in doors of this type, it has been the practice to connect each of the door sections 25 by flexible suspension means, with a counterweight, said suspension means passing over ordinary pulleys mounted in the elevator shaft adjacent and above the door opening, the suspension means connected with the slower moving door section being passed about a pulley upon said door section and the end thereof being secured adjacent the pulley in the elevator shaft so as to cause that door section to move at exactly 35 one half the speed of the other section.

In a door made in accordance with my invention, I am not only enabled to dispense with the pulley upon the more slowly moving door section, but provide a structure 40 wherein the counterweight does not act directly upon either door section through the suspension means therefor, but acts upon an intermediate shaft from which both the said doors are suspended, the construction of this 45 intermediate shaft and the means carried thereby cooperating with said suspension means, being such as to permit the desired varying speeds of the various door sections. By this construction two or more door sections may be used, the comparative sizes of which is capable of any desired variation, since the device upon the shaft with which each of the doors is connected, may be made to conform to any size or weight of door irrespective of any definite ratio of relative

speeds such as must be preserved when pulleys are used as heretofore. The variance in the speeds of the door sections is secured by a variance in the leverage of the means with which the suspension means is operatively connected, and hence the counterweight used need not equal the aggregate weight of all of the door sections but is determined by the relative leverages of the mechanisms operative to raise said doors 60 and of the operative leverage by which the operative moment of said weight is transmitted to said shaft. I also preferably so construct the means upon the rotatable shaft coöperating with the suspension means, as to 70 minimize any possibility of the suspension means being displaced with relation to their coöperating means by reason of the slackness in the suspension means due to a sudden stoppage of the door sections following a 75 rapid movement thereof.

It is apparent that my invention may be adapted with equal facility to a door in which the sections move either upwardly or downwardly, it being merely required, to 80 change from one style of door to the other, to reverse the arrangement of the suspension means. I also provide guiding means to guard against side swaying of the door sections which means are so constructed as to 85 permit expansion of the doors in the event of fire in and about the elevator shaft, without jamming the door. I also provide stiffening guides carried by each door section intermediate the side edges thereof, which 90 guides coöperate with the sill or with the lintel, at the doorway, and with guides upon the other door section in a manner to prevent warping of the doors adjacent the center thereof with a resultant disarrangement 95 in the suspension mechanism. I also provide in connection with the lowermost door section of upwardly moving doors, a locking mechanism coöperating with a keeper on the door sill, the opening of which will result 100 from the application of force thereto applied in a direction to raise the door.

The invention consists in the novel features of construction and combination of parts hereinafter set forth and described 105 and more particularly pointed out in the claims hereto appended.

In the accompanying drawings in which like letters of reference indicate like parts in all the figures: Figure 1 is a face view of 110

one embodiment of my new and improved door, closed, parts being broken out and others shown in section. Fig. 2 is a horizontal sectional view on the line *a—a* of Fig. 1. Fig. 3 is a vertical sectional view on the line *b—b* of Fig. 1. Fig. 4 is a detail perspective view of the door sections, their guides and other parts, parts being broken away and others shown in section. Fig. 5 is a perspective view of the two doors in position when closed, parts being broken away and others shown in section. Fig. 6 is a horizontal sectional view showing a construction of the guides for use on masonry, walls without an iron skeleton, sunk into the wall so as not to interfere with movements of the weight. Fig. 7 is a detail perspective view of the latch, parts being broken away. Fig. 8 is a vertical sectional view of the latch, with the removable key for opening the doors from the loft side, on the line *d—d* of Fig. 7. Fig. 9 is a face view of my improved doors so hung that the sections open downward and the upper door is practically flush with the floor when the doors are open, to form a truckable sill, parts being broken away. Fig. 10 is a cross sectional view of parts of the construction shown in Fig. 9, both doors being lowered into open position and practically flush with the building floor.

In Figs. 1 to 8 of the accompanying drawings, I have shown the embodiment of my invention in an elevator door comprising a lower section A, and an upper section B, each of which sections is of substantially the same size, weight and construction as the other. The detail construction of these sections is immaterial to my present invention as they may be made in accordance with any well known or approved practice for resisting heat and flame. In the accompanying drawings, each of these door sections is shown as being composed of a T-iron frame 1, supporting a corrugated sheet metal sheathing 2, riveted, bolted or otherwise secured thereto.

Adjacent each side of the door opening in the elevator shaft is a vertically extending angle iron 6, one flange of which projects into the shaft and has secured thereto two vertically extending guides 5, formed of angle iron, one flange of each of which is secured to the inwardly directed flange of the angle iron 6, the other flange 4 thereof extending perpendicularly thereto upon parallel vertical planes to insure the desired overlapping of the door sections. In the accompanying drawings, the door opening is shown as having a metallic frame composed of the channels 7, the angle irons 6 being secured to said channel and projecting with the guides 5 upwardly beyond the lintel of the door sufficiently to permit both door sections to pass above said lintel.

To prevent side swaying of the door sections A—B and at the same time permit expansion thereof in the event of overheating from fire or flame, I provide the opposite edges of each section with expansion pieces 8 or members 8 consisting of a narrow strip of metal riveted or otherwise secured to the said frame and projecting outwardly therefrom into engagement with the top of the flange 4 of the guides 5. The expansion pieces or members 8 are made of metal stock sufficiently light to permit their being bent toward or from the said frame either under pressure resulting from the expansion of the door section, or by means of tools in fitting the door section. By having said expansion pieces or members bear upon the top of the flange 4, they are readily accessible for fitting purposes. To insure the expansion pieces or members 8 remaining in the desired running engagement with their respective flange 4, I provide the frame 1 with forked guides 13 straddling the edge of said flange. These guides are to insure a substantially vertical movement of the door as well as to preserve the proper relation of the expansion pieces or members 8 with the vertical guides 5.

Carried by the lower door section are one or more vertically extending retaining bars 9 having an extended head slidably mounted in a shoe 10 carried by the upper section B, thus insuring not only the movement of the two sections A and B in parallel planes but also imparting sufficient rigidity to the portion of the door section A intermediate the guides to prevent warping thereof. Said retaining bars 9 are attached directly to the corrugated sheathing 2 of the door, the opposite ends thereof being reduced to receive the web of the frame 1 to which said bars are also firmly secured by riveting or otherwise.

The shoes 10 are secured to the section B by means of an angle iron 12, one flange 11 of which extends vertically and is presented toward the section A and the other flange of which is secured to the base of the T-iron bottom bar 1 of the said section B. The shoes 10 in addition to serving as guides for the bars 9 also act as stops with which the base of the top frame 1 of the section A is adapted to engage when the doors are closed. The shoes 10 are provided with elongated slots, as shown in Fig. 5, for the purpose of permitting any adjustment thereof which may be necessary to secure the desired vertical movement of the door sections.

The section B is provided with one or more retaining bars 13, similar in construction and operation to the bars 9, the bars 13 coöoperating with shoes 14, (similar to the shoes 10) carried by the lintel 15 at the door opening. To limit the downward

movement of the section B in the event of the breakage of the suspension means therefore, I provide the top bar of the frame of said section with a plate or plates 16 adapted to project therefrom in a manner to engage the shoes 14.

Mounted in a suitable bearing piece or block 19, preferably bolted or otherwise secured to the angle irons 6, are shafts having 10 mounted thereon and rotatable therewith sprocket wheels 18 and 21 adapted to cooperate with suspension means for the door sections A and B in raising and lowering said sections in opening and closing the 15 door. Connected with the section A and passing over the sprocket wheel 18, is a sprocket chain 17 and connected with the section B and passing over the sprocket 21 is a second sprocket chain 22, ease in the 20 movement of said door sections in opening the door resulting from the rotation of the shaft carrying said sprocket wheels 18 and 21 under the influence of the counterweight 20 operative upon said shaft and said 25 wheels. In closing the door, the load of the sections A—B is resisted by said counterweight, ease in the movement of said sections resulting from the application of the aggregate weight of said door sections, applied through the suspension means, to turn 30 said sprocket wheels in the reverse direction. In the form of the invention shown I apply the load of the counterweight 20 to the sprocket wheels 18 and 21 by attaching 35 said weight to the end of the chain 17.

In the accompanying drawings the invention is shown as applied to a two section door, the upper section of which moves at substantially one half the speed of and 40 simultaneously with, the lower section. Under this condition the sprocket 21, will be one half the diameter of the sprocket 18, thus causing the peripheral velocity of said sprocket 21 to be just one half that of the sprocket 18 with a resultant proportionate 45 rate of travel of the two door sections A and B. Inasmuch as the counterweight 20 acts upon a radius of the sprocket wheel 18 which is twice the radius of the wheels 21 50 it is apparent that the combined weight of the counterweights acting on the two door sections need be but about three quarters of the weight of these sections to secure a reliable counterbalancing thereof. Where 55 more than two sections are used, the gross weight of the counterweights may be determined by the relative weights of the several sections, the diameters of the sprocket wheels coöperating with the chains used in 60 suspending each section and the leverage at which the counterweights act upon the shafts carrying the several sprocket wheels. It will be observed that the chains 22 are not 65 connected with the counterweights 20. To minimize likelihood of the chains 17 and 22

loosing their mesh with the sprocket wheels 18 and 20 respectively, I provide each of said wheels with shrouds as shown and also provide the block 19 with guard sections projecting over said sprocket wheels in close proximity to the teeth thereof so that in the event of slackness in the chain through a sudden stoppage of the door section, said chains cannot overrun the sprocket teeth in a manner to become disengaged from their respective wheels. By using sprocket wheels and sprocket chains, I secure a positive connection between the flexible suspension means for the door sections and the means coöperating therewith, the counterweighting of the doors being effected by the application of the desired weight to the said sprocket wheels or other means, as distinguished from the application of the weight directly to the doors or door sections through suspension chains or cables passing over anti-friction rollers or pulleys.

The sill 23 is provided with two undercut slots 24 for receiving hooks 25 formed on the ends of angle levers 26 pivoted at 27 to the lower door, the upper ends of the angle levers being connected by bars 28 with a vertically sliding plate 29 held in place by a keeper 30. The plate 29 has a notch 31 for receiving an arm 32 mounted on a pin 33 passing through the door. The plate 29 can be raised by means of a top flange 35 and 36 is a safety pin to prevent the flange 35 from contacting with the top of the keeper 30 and bruising the fingers. The pin 33 projects into a bushing 37 and is provided with a cross piece 38 fitting into one end of a tubular key 34 which is notched to receive the cross piece 38. A helical spring 39 in the tubular key serves to throw out and disengage the key from the cross piece 38 as soon as the key is released.

In Figs. 9 and 10 I have shown the doors arranged to slide downward in opening, and upward in closing. The relations of the chains, sprocket wheels and weight remain the same, but the chain to which the upper door is attached is now the one which carries the weight and the lower one is attached to the chain without the weight and passing over the smaller sprocket wheel. The doors when lowered are substantially flush with the floor 40 as shown in Fig. 10. An angle iron 41 is attached to the top of the frame of the upper door A' and extends over the top edge of the lower door B' as well as that of the upper door A' when the doors are lowered. 42 is a filler between the flange of the angle 41 and the corrugated iron. A stop lug 43 is attached to the guides and can contact with the ends of the top bar 41 of the upper door A' to form a positive stop so that trucks can be passed over the lowered doors when the angle iron 41 is flush with the floor 40, without in any 130

way injuriously affecting the chains. In this form of the invention, the top bar 41 in addition to the support received at the ends thereof from the lugs 43, will be supported intermediate said lugs by the guide bars 9 as well as the T-bar constituting the top of the frame of the section A. In this form of the invention the operation of the various parts in raising and lowering the door sections in opening and closing the door, will be substantially as heretofore described, the arrangement shown in Figs. 9 and 10 being a mere reversal of the arrangement shown in the remaining figures of the drawing.

Having described my invention what I claim as new and desire to secure by Letters Patent is:

1. A vertically sliding door for elevator shafts embodying therein a plurality of sections, parallel guides for said section, independent suspension means for each of said sections, rotary members of different diameters to which said suspension means respectively are positively connected, said members being adapted to rotate in unison and a counterweight positively connected with and simultaneously acting upon said rotatable members whereby the load of said counterweight will be applied to said members and will be transmitted through said members to said suspension means and said door sections.

2. A vertically sliding door for elevator shafts embodying therein a plurality of sections, parallel guides for said section, independent suspension means for each of said sections, rotary means of different diameters to which said suspension members respectively are positively connected, said members being adapted to rotate in unison and a counterweight positively connected with and simultaneously acting upon said rotatable members whereby the load of said counterweight will be applied to said members and will be transmitted through said members to said suspension means and said door sections, the load of said counterweight being applied to said rotary members at a leverage greater than that of the average diameter of said members.

3. A vertically sliding door for elevator shafts embodying therein a plurality of sections, parallel guides for said sections, a plurality of sprocket wheels of different diameters mounted upon and rotatable with arbors common thereto, sprocket chains passing over said wheels respectively and connected with said door sections respectively whereby each of said sections is positively and independently connected with its sprocket wheel and a counterweight positively connected with and simultaneously acting upon said sprocket wheels whereby the load of said counterweight will be ap-

plied to said wheels and will be transmitted through said wheels to said suspension means and said door sections.

4. A vertically sliding door for elevator shafts embodying therein a plurality of sections, parallel guides for said sections, a plurality of sprocket wheels of different diameters mounted upon, and rotatable with, arbors common thereto, sprocket chains passing over said wheels respectively and connected with said door sections respectively whereby each of said sections is positively and independently connected with its sprocket wheel, means whereby the disengagement of said chains with said wheels respectively is prevented, and a counterweight acting upon said sprocket wheels whereby the load of said counterweight will be applied to said wheels and will be transmitted through said wheels to said suspension means and said door sections.

5. A vertically sliding door for elevator shafts embodying therein a plurality of sections, parallel guides for said sections, a bearing piece, a plurality of sprocket wheels of different diameters mounted upon, and rotatable with, arbors common thereto mounted in said bearing piece, said sprocket chains passing over said sprocket wheels respectively and being connected with said door sections respectively whereby each of said sections is positively and independently connected with its sprocket wheel, said bearing piece being provided with guard sections projecting over said sprocket wheels in close proximity to the teeth thereof, and said sprocket wheels being provided with shrouds whereby the disengagement of said chains with said wheels respectively is prevented, and a counterweight acting upon said sprocket wheels whereby the load of said counterweight will be applied to said wheels and will be transmitted through said wheels to said suspension means and said door sections.

6. A vertically sliding door for elevator shafts embodying therein a plurality of sections, parallel guides for said sections, independent suspension means for each of said sections, rotary members of different diameters to which said suspension means respectively are positively connected, said members being adapted to rotate in unison, a counterweight positively connected with and simultaneously acting upon said rotatable members whereby the load of said counterweight will be applied to said members and will be transmitted through said members to said suspension means and said door sections, and means whereby side swaying of the door is prevented.

7. The combination with two door sections, mounted to slide vertically and overlap, of a sprocket chain attached to one door section, a sprocket wheel over which said chain

passes, a weight attached to the opposite end of said chain, a sprocket wheel connected with the above mentioned sprocket wheel, a separate sprocket chain passed over said 5 second sprocket wheel and connected with the other door section, only, substantially as set forth.

8. The combination with two door sections mounted to slide vertically and over-
10 lap, of a sprocket chain attached to one door section, a sprocket wheel over which said chain passes, a weight attached to the opposite end of said chain, a sprocket wheel connected with the above mentioned sprocket 15 wheel, a separate sprocket chain passed over

said second sprocket wheel and connected with the other door section, only, the sprocket wheel over which the chain not connected with the weight passes, being of less diameter than the sprocket wheel over 20 which the chain passes that is connected with the weight, substantially as set forth.

Signed at New York city, borough of Manhattan in the county of New York and State of New York this 1st day of September 25 A. D. 1915.

-BENJAMIN WEXLER.
